ATTY.

UNITED STATES PATENT OFFICE.

HARRY SMITH, OF PORTLAND, OREGON.

LINOTYPE-INSTRUCTION DEVICE.

1,390,550.

Specification of Letters Patent. Patented Sept. 13, 1921.

Application filed July 24, 1920. Serial No. 398,751.

To all whom it may concern:

Be it known that I, HARRY SMITH, a citizen of the United States, residing at Portland, in the county of Multnomah and State 5 of Oregon, have invented a new and useful Improvement in Linotype-Instruction Devices, of which the following is a specification, reference being had to the accompanying drawings.

10 My invention relates to devices having character key-boards as a class.

The object of my invention is to provide a linotype keyboard in relation with a typewriter machine of common type, in a manner whereby the mechanism of the typewriter may be operated automatically by the linotype key-board mechanism, to produce prints of visible characters corresponding to those required by the linotype. This 20 object, as well as other advantages, I attain by the construction, combination and arrangement of parts shown in the accompanying drawings which form a part hereof.

Figure 1 is a side elevation of linotype key mechanism and typewriter mechanism above it, parts being in section, and partly on the line I—I in Fig. 2.

Fig. 2 is a front elevation of the upper part of the linotype key mechanism and typewriter mechanism above, and showing intermediate mechanism.

Fig. 3 is a plan view of intermediate levers from the linotype striking pins to the drawing rods showing change in courses.

35 Like characters refer to like parts in the views.

A linotype key mechanism case 4 is illustrated. It has therein keys 5, key levers 6 and striking pins 7, with intervening mechanism 8, between the levers 6 and pins 7, all 40 of which is of the common type usually found in linotype or type casting machines. The intervening mechanism outlined in Fig. 1 as a part of the linotype machine shows; 45 the usual continuously rotating power shaft 8^a, a horizontal bar 8^b pivoted at one end in the case above the shaft, the vertical pin 7 rigidly secured at its lower end upon the opposing end of the said bar, a cam member 8^c pivoted in the central part of the horizontal bar above the shaft in position to be dropped into engagement therewith, a vertical arm 8^d engaging at its lower end the inner end of the key lever 6, a cam lever 50 8^e pivoted near the upper end of the vertical arm, one end of the lever engaging this arm

near its upper end, the opposing end of the lever positioned to raise the horizontal arm and thereby lift its cam member out of engagement with the shaft or allow it to drop 60 to engagement therewith. A typewriter case 9, in part, is also shown. It has therein typewriter keys 10, key levers 11, type bars 12, means 13 to connect the levers 11 and bars 12. It also has a platen 14, adapted 65 to engage and rotate paper in a position to receive imprints thereon from the type 15 on the bars 12. On the upper part of the case 4 a transverse shaft 16 is rigidly mounted. Along this shaft a series of levers 17 70 are pivoted thereon with spacing collars 18 between them. One free end of each of these levers is arranged above a desired striking pin 7 of the linotype mechanism, the lever is angled on the opposing side of the pivot 75 shaft in a desired direction to bring the opposing end of the lever below the outer end of a corresponding typewriter key lever 11. A rod 19 is pivoted at its lower end in this opposing end of the lever 17, and extends 80 upwardly to a pivoted connection with the corresponding typewriter lever 11 near its key 10.

It will now be seen that when a linotype key is struck by the operator, for example 85 the key bearing the character A, the cam lever is caused to move sufficiently to allow the horizontal bar to drop its cam member into engagement with the power shaft, which automatically causes the member to 90 make a revolution and the pin 7 to rise. Thereupon the pin 7 engages the lever 17, which in turn automatically draws the rod 19 downwardly and the rod depresses the corresponding typewriter key lever 11, and 95 thereupon the type bar 12, bearing the character A, is actuated. This causes the type to strike the paper in the usual manner of typewriters, and makes its imprint of the character A on paper held for the reception 100 thereof on the platen 14. It is well known that the linotype keyboard is longer than the key frame of the typewriter, hence it is necessary to arrange the levers 17 at suitable angles between the linotype striking 105 pins and the positions of the typewriter key levers above. It is intended that the typewriter shall be secured in any suitable manner above the linotype key case to retain both rigidly in relation to each other. The 110 principle of my invention lies in the connecting of the linotype key mechanism with the

22
 typing mechanism of the typewriter, without material change of parts in either. It is well known that those desiring to learn the operation of a linotype key-board cannot 5 do so on a complete linotype, without either using the entire mechanism to form finished cast type, or they must strike the keys with the casting mechanism cut off. In the latter case there is no means provided where-
 10 by the practising operator may know whether or not he is striking the keys correctly to make type corresponding to the copy before him. This is overcome by arranging the typewriter with the linotype 15 keyboard, and the actual imprint result of each linotype key struck, is at once registered and made visible by the imprint of the typewriter type.

While I have shown a practical and operative mechanism between that of the linotype and the typewriter, I do not limit myself to the precise form thereof, but contend that the principle involved embraces any suitable and desirable intermediate mechanism 25 of like character, intended to produce the same result described. Therefore, in the construction of my device, I assemble the linotype key mechanism apart from the remainder of the linotype, a typewriter ar-
 30 ranged in a suitable position with relation to the said linotype mechanism, and then connect the first and second mechanisms with a desired intermediate means, whereby the second may be operated automatically 35 by the operation of the first mechanism only. It is also intended that the intermediate means shall be adapted to any common character arrangements of both linotype and typewriter mechanisms. In this way the use
 40 or necessity for any special form or arrangement of either is obviated. This makes the present device very economical and is new and useful. At present those desiring to

learn the operation of a linotype are unable to do so as rapidly and efficiently as should be the case, because of the expense in operating a complete linotype, or the inability to obtain a view of the results of actual work done. These and other difficulties are overcome by my device.

45 I claim—

50 A device of the character described, hav-
 ing in combination therein, a linotype key-
 board mechanism of common type with a
 power transmission shaft extending within
 the casing thereof, a horizontal bar pivoted
 55 at one end in the casing above the shaft,
 with a rigid vertical pin on its opposite
 free end, a cam member pivoted in the bar
 above the shaft, a slidable vertical arm en-
 gaging at its lower end an opposing linotype
 60 key-bar, a cam lever pivoted near the
 upper end of the arm in position where one
 part of the lever engages the upper part of
 the arm and the opposing lever part sup-
 ports the bar in sliding engagement there-
 65 with, a typewriter mechanism of common
 type, and a lever pivoted at its center on the
 linotype case, its free end extending over
 the free end of the aforesaid pin, and having
 a rod extending from its opposing end to a
 70 desired typewriter key-bar, the whole being
 arranged to allow the cam lever to be man-
 ually moved to permit the bar to drop suffi-
 ciently so that its cam member may engage
 the shaft, and the shaft automatically to
 75 cause said member to raise the free end of
 the bar and the end of its pin to deliver an
 impact stroke to the intervening mechanism
 and it in turn to actuate a desired type key-
 bar to an impression.

80 HARRY SMITH.
